(57) **CLAIM**

The ornamental design for a bag with closure as shown and described.

DESCRIPTION

FIG. 1 is a top plan view of a bag with closure, showing the new design in a closed configuration;
FIG. 2 is a bottom plan view thereof;
FIG. 3 is a top perspective view thereof;
FIG. 4 is an enlarged right side elevation view thereof;
FIG. 5 is an enlarged left side elevation view thereof;
FIG. 6 is a front elevation view thereof;
FIG. 7 is a rear elevation view thereof;
FIG. 8 is a top plan view of the bag with closure in an opened configuration;
FIG. 9 is a bottom plan view thereof;
FIG. 10 is a top perspective view thereof;
FIG. 11 is a right-side elevation view thereof; and,
FIG. 12 is a left side elevation view thereof.
The evenly broken lines represent parts of the article that form no part of the claimed design. The short-dash-long-dash broken lines represent the boundaries of the claim and form no part thereof.

1 Claim, 12 Drawing Sheets
